UNITED STATES PATENT OFFICE.

MILTON ALDEN, OF SPRINGFIELD, MASSACHUSETTS, ASSIGNOR TO DENTAL ELECTRIC COMPANY, OF SPRINGFIELD, MASSACHUSETTS, A CORPORATION OF MASSACHUSETTS.

ILLUMINATING APPLIANCE.

1,311,790.

Specification of Letters Patent. Patented July 29, 1919.

Application filed November 12, 1917. Serial No. 201,718.

To all whom it may concern:

Be it known that I, MILTON ALDEN, a citizen of the United States of America, residing in Springfield, in the county of 5 Hampden and the State of Massachusetts, have invented certain new and useful Improvements in Illuminating Appliances, of which the following is a specification.

This invention relates generally to supporting devices for electric lamps and more particularly to an improved electric lamp appliance, which is particularly adapted for illuminating the interior of the mouth to facilitate dental, surgical, and other operations.

It is recognized that various devices have been heretofore provided for supporting an electric lamp within the mouth of a patient. The prior lamp supporting devices used for this purpose, have, so far as I am aware, been constructed so that the flexible conductor cord extends out of the patient's mouth in such a manner that it is either continually in the way of the dentist or may readily move into a position to interfere with free access to the mouth. Generally also the lamp is supported by clamps from the patient's teeth or cheek or other equivalent means which are unpleasant and uncomfortable to the patient. Many of the devices heretofore provided are also bulky, awkward, and so arranged that they occupy an unduly large part of the patient's mouth, leaving little room for dental operations. This invention is concerned, among other things, with the elimination of the above mentioned disadvantages.

An object of the invention is to provide a supporting device for an electric lamp, 40 which is adapted to hook around a corner of the patient's mouth with the lamp positioned therein and to direct the electrical conductors for the lamp toward the back of the patient's head, together with means 45 to suspend the support from the patient's ear, the construction being characterized in that the lamp may be supported within the mouth without discomfort to the patient and without materially obstructing 50 or interfering with free access to the mouth. Other objects and advantages will appear in the following description and appended claims.

The invention, in an embodiment at present preferred, is disclosed for illustrative

purposes in the accompanying drawings, in which—

Figure 1 is a plan view of the lamp, its connections, and supporting member;

Fig. 2 is an elevational view of a portion 60 of Fig. 1;

Fig. 3 is a cross sectional view of the lamp supporting arm;

Fig. 4 is a profile view illustrating the manner of supporting the lamp within a 65 patient's mouth; and

Fig. 5 is a face view showing the lamp as supported within the mouth interior.

Referring to these drawings in detail; a suitable socket 8 is arranged to receive an 70 electric lamp 7 in the usual manner. The socket, however, is preferably of insulating material and is constructed similarly to the well-known water-proof and weatherproof sockets, to guard against the entrance of 75 saliva into its interior and to prevent possible injury to the patient from accidental electrical shock. Socket 8 is suitably attached to the short leg of an arm 9, bent into substantially hook form, and arm 9 80 is purposely made hollow, as shown in Fig. 3, so that electrical conductors 10 may be conveyed therein from the socket to suitable terminals. The latter may be of any suitable type but, preferably for convenience, 85 they consist of a pair of pins 11 (Fig. 2) secured in and projecting from an end of an insulating block 12 fixed on the end of the long leg of arm 9. A female socket member 13 is provided with spaced holes 90 to receive pins 11, whereby a slip joint electrical connection between the conductors within arm 9 and a flexible conductor cord 14 may be made in a now well known manner. Preferably, a closely wound coiled 95 spring 15 is slipped over cord 14 and is suitably fixed to the member 13 for the purpose of preventing the cord from bending sharply adjacent its connection to the latter. The spring 15 is substantially similar to 100 and accomplishes the same function, as the spring used as a protective means on the flexible cords of electrical flat irons and the like. A bow 16 of spring wire, similar to the bow used in spectacles, is connected 105 to turn on the part 15 by loosely coiling its lower end around the latter as indicated in Fig. 1.

In use, the arm 9 is hooked around one corner of the patient's mouth with the short 110

leg of the arm positioned within the latter. The members 12 and 13 are then connected and bow 16 is hooked around the patient's ear, as indicated in Fig. 1. The cord 14 is, 5 of course, connected to a suitable source of electricity to illumine lamp 7. When the parts are thus positioned, the rays from lamp 7 are directed upon the side of the jaw and mouth interior opposite to that on which it 10 is located. By reason of its pivotal connection with part 15, the bow 16 may be swung through an arc of substantially 180 degrees, whereby the support is reversible and may thus be similarly supported from the other 15 side of the patient's head.

The arm 9 may be made so that there is a slight amount of spring between the long and short legs thereof, whereby when the arm is positioned as described, there will 20 be a slight clamping pressure on the patient's cheek to aid in supporting the lamp. While such construction may be used if desired, it is not, however, essential as the hook-shaped arm, loosely engaging a corner 25 of the mouth and supported by bow 16 from the ear, furnishes a satisfactory support for the lamp and is preferred.

A most important and advantageous feature of the construction described is in the 30 arrangement whereby the electrical wires supplying the lamp are held out of the way of the dentist or surgeon. The outer leg of arm 9, when supported as described, lies substantially contiguous with the patient's 35 cheek and extends rearwardly from the mouth so that it cannot in itself interfere with free access to the mouth of the patient. The inner leg of arm 9 is similarly positioned closely adjacent the inner wall of the 40 patient's cheek. The supply wires, being conveyed through the hollow arm 9, are directed toward the back of the patient's head. Thus the flexible cord, being supported from the ear of the patient, cannot readily get in 45 the way of the dentist, and its natural tendency is to pass over the patient's shoulder, as distinguished from the devices heretofore used for similar purposes, wherein the flexible cord is without means to direct its course 50 and accordingly tends to get directly in the way and obstruct the mouth opening.

The lamp supporting device is thus characterized in that it may be supported in a patient's mouth without injury or discom- 55 fort to the patient and in the arrangement of parts, whereby the lamp may be sup-

ported in the described way without causing a material obstruction in or interfering with free access to the patient's mouth.

The invention has been described herein 60 for illustrative purposes, but the scope of the invention is defined by the appended claims rather than by the foregoing description.

What I claim is—

1. A mouth illuminating appliance, comprising, an electric lamp, a lamp supporting means having a part adapted to be positioned within the mouth and another part bent backwardly upon the first-named part 70 in spaced relation therewith and adapted to be positioned adjacent the cheek and extend rearwardly thereof, and means adapted to suspend the last-named part from the ear. 75

2. A mouth illuminating appliance, comprising, a substantially hook-shaped member having means at one end to support an electric lamp, electric conductors extending from said means and guided by the member to its other end, said member adapted to be 80 hooked around one corner of the mouth with said means positioned therein, and means adapted to engage the ear and pivotally suspend the last-named end therefrom. 85

3. An illuminating appliance, comprising, a hollow supporting device bent into substantially hook form and provided at one end with means to receive an electric lamp, conductors from the latter extending through 90 said device and emerging from the other end of the latter, and a member having a hook at one end and its other end loosely coiled around said conductors adjacent the last-named end of said device. 95

4. A mouth illuminating appliance, comprising, an electric lamp, a lamp supporting means having a part adapted to be positioned within the mouth and another part bent backwardly upon the first-named part 100 in spaced relation therewith and adapted to lie adjacent the cheek and to extend rearwardly therefrom toward the ear, and electric conductors extending from said lamp along and guided by said means, said means arranged to be hooked around one corner of the mouth without obstructing the latter and said conductors being guided by said means away from the patient's mouth and toward the rear of his head. 105

MILTON ALDEN.
